UNITED STATES PATENT OFFICE.

CHARLES W. WILDER, OF FITCHBURG, MASSACHUSETTS.

WOOD-TURNING LATHE.

SPECIFICATION forming part of Letters Patent No. 242,242, dated May 31, 1881.

Application filed January 8, 1880.

To all whom it may concern:

Be it known that I, CHARLES W. WILDER, of Fitchburg, in the county of Worcester and State of Massachusetts, have invented certain 5 new and useful Improvements in Wood-Turning Lathes, of which the following is a specification.

My invention relates to that class of lathes for rapidly forming various small wooden articles of regular shapes—such as spools, pill-boxes, handles, &c.—the beds of which are equipped with a fixed head-stock, a sliding tail-stock, and a central sliding tool-holding carriage, the head-stock having a chuck to 15 hold and revolve a long stick of wood, from which a number of articles may be successively turned, while the central carriage is fitted with a guiding-socket to receive the roughed-out end of the stick, with roughing-out tool on the 20 front side thereof, and shaping and cutting-off tools on the tail side thereof, which latter are actuated by a knee-lever, while the tail-stock carries a boring-tool for simultaneously boring the work.

My present invention is more especially an improvement on the patent of A. D. Waymuth, of August 11, 1857, No. 18,001, and is embodied mainly in the tool-carriage, and relates to the adjustable mounting of the roughing-tool, 25 the manner of mounting the cutting-off tool, the construction of the knee-lever and its operative connection with both the shaping and cutting-off tools, the construction of the underlying guide-gibs of the sliding stocks or carriage, the arrangement of the spring which 30 causes the tools to retire, and in other features, as hereinafter fully set forth.

Figure 2 of the annexed drawings presents a plan view of my improved lathe, and Fig. 1 40 a front elevation thereof. Fig. 3 is an enlarged transverse view of the tool-carriage from the rear wall, and Fig. 4 a view of the same from the front side. Fig. 5 is a front-end elevation of the tail-stock. Fig. 6 is a sectional detail, 45 showing the mode of adjusting one of the tool-holders.

As illustrated, A indicates the bed of the lathe, fitted at one end with the usual fixed head-stock, B, and at the opposite end with 50 the sliding tail-stock C, while between the two the sliding tool-carriage D is arranged. The

spindle of the head-stock is terminated with the usual chuck, d, to hold and revolve the wooden stick, and which, preferably, has a conical mouth, in which a screw-thread is formed 55 to engage the end of the stick. The spindle of the tail-stock is adapted to hold a boring-tool, as shown, for work requiring it, and the tail-stock is also provided with a tool-post, e, for holding a tool to act on the end of the stick, 60 for forming a tenon or other terminal thereon when required. Adjustable stop-screws f g project respectively from the face of the head and tail stocks, to limit the movement of the tool-carriage and tail-stocks. 65

All of the parts above referred to are about of the usual construction, and the lathe is operated and the work performed thereon in the usual manner, which, hence, requires no further description. The bed of the lathe, however, 70 is formed with the approved A-ways, on which the tool-carriage and tail-stock slide, instead of the old rabbet form of way, which improved ways secure a more accurate alignment of centers and prevent undue play or wear. 75

It will be also observed that the rack and pinion for moving the tail-stock formerly employed is dispensed with and a hand-lever substituted, which is simpler and quicker in its action. 80

Now the main novel features of my invention are embodied in the tool-carriage D, as will be now described. From the base of this carriage, and about midway thereof, the usual upright web, h, rises. This upright has a central opening to receive rings i, which have a flaring mouth, which the stick first enters, and a central bore, of size corresponding to the rough 85 diameter of the work, to form a guide and socket for the same to turn in, as usual. 90

The roughing-out tool k, which cuts off the corners from the stick and reduces it to a size to enter the socket of the ring i, is mounted on the front side of the upright, and projects obliquely into a radial gap in the socket-ring i, 95 while the shaping and cutting-off tools l m are arranged in appropriate holders on the opposite side of the upright, and are brought into action by the knee-lever n, projecting from the carriage below the bed of the lathe, in the usual manner. According to my present invention, 100 however, the roughing-tool k is clamped in an

adjustable holder, *o*, supported on a lug, *p*, projecting from the front face of the web *h*. This lug has **A**-guides, which match with similar grooves on the under side of the holder *o*, and thus insure a parallel movement, while the holder has a downwardly-projecting neck, which is guided in a square slot or cleft in the lug *p*, and this neck is terminated with a **T**-head or cross-flanges, which together effectually guide and steady the adjusting movement of the holder to or from the face of the upright. A tight-fitting set-screw, *r*, screwed through the neck of the holder, passing into the lug, and having its end riveted to prevent its coming out, as shown in Fig. 6, enables the holder to be set with great nicety and positiveness, thus causing the roughing-cutter to be set closer to or farther from the guide-socket ring *i*, so as to give the knife more or less cut, which is an important advantage over the holder previously used.

The holder *a* for the shaping-tool and the holder *b* for the severing-tool are both mounted in or over an opening in the base of the carriage, between the main upright *h* and a shorter upright, *c*, on the rear of the carriage, and the actuated portions of the holders depend through this opening, between the ways of the lathe, and connect with the knee-lever *n*. According to my invention each of these holders is pivoted independently and connected independently to the knee-lever.

The severing-tool holder *b*, as shown, is a lever-bar disposed horizontally, and pivoted on its front end on the pin or stud *t*, its outer end being slotted to receive the severing-cutter, which is held in the socketed head of a screw-stud adjustable in said slotted end. The pivot end of the holder is formed, as shown, with a cleft eye, which is clasped on the pivot-stud *t* by a clamping-screw, *x*, by which it may be fixed firmly thereon or set farther forward or backward, so as to bring the point of the cutter closer to or farther from the face of the upright *h*, as will be understood. The pivot-stud *t* is pointed at one end and countersunk at the other, the pointed end pivoting in a countersunk hole in the face of the upright *h*, while the countersunk end pivots on the point of a tight stud, *c'*, screwed through the other upright, *c*. By this construction and arrangement of the holder *b* it will be observed that the severing-cutter will rise against the work in the most effective direction, and in being pivoted at a long leverage its motion is almost frictionless, while ample and easy adjustment, both lengthwise and transversely, are provided, which is an important advantage over the sliding holders previously employed, which move with much friction, and in which the adjustment is usually effected by bending the cutter.

The holder *a* for the shaping-tool is of bent lever form, being pivoted on studs *u* a little beyond and below the pivot of the other holder, its long arm depending vertically beneath the carriage, while its short arm is bent slightly for-

ward and terminated with the usual broad head to receive the usual shaping-cutter.

The knee-lever *n*, which operates these tool-holders, is pivoted on a lug, *v*, which depends from and forms part of the underlying gib, *v'*, of the tool-carriage, which holds the carriage from rising off the ways; and this construction of the gib forms a minor feature of my invention, which conduces to compactness and simplicity. The knee-lever is formed, as shown, with a segment of gear-teeth, *y*, on its upper and shorter arm, which mesh with a small gear-wheel or section of a gear-wheel, *w*, which is mounted on an axial pin fixed to a lug, *d'*, which depends from the base of the tool-carriage. This gear-wheel or pinion *d'* carries a projecting crank-pin, *c*², which is connected by a short pitman or link, *z*, to the long arm of the shaping-tool holder *a*, and also by a separate and longer pitman, *t'*, with the free end of the severing-tool holder *b*, this latter pitman being made in two extensible parts, as shown, whereby its length may be adjusted to give the severing-tool the desired movement. The leverage and arrangement of the two tool-holders relatively to each other and to the crank-pin is such that the severing-tool holder is given a much larger motion than the shaping-tool holder; but the movement of the former is chiefly idle. The first movement of the crank moves the shaping-tool slowly against the work, reducing the same to finished shape, when the crank then reaches its dead-point relatively to this tool, which hence remains stationary; but this position of the crank now becomes the point of greatest action on the severing-tool, whose previous motion was idle, but now becomes quickly forced into the work, thus severing the shaped article by its terminal movement. When the lever *n* is released from the pressure of the knee a spiral or coiled spring, *c*³, on the hub of the crank-wheel *w*, which was coiled by the previous motion, now reacts and causes the tools to at once retire from the work and brings the several parts into their position of repose. One terminal of this spring contacts against a continuation of the crank-pin *c*², which projects from the opposite side of the crank-wheel *w*, while the other terminal engages with the teeth of a ratcheted head, *j'*, on the end of the axial stud on which the crank-wheel turns, so that by engaging this end of the spring with one or other of the ratchet-teeth its tension will be adjusted in a very simple and effective manner, which forms an additional feature of my invention.

In connection with the **A**-ways of the lathe and the sliding carriages or stocks I employ fixed gibs *v' v*², to hold the same in place, which gibs are rigidly fixed to the bases of the carriages, as seen in Figs. 3, 4, and 5, and underlie the ways, as shown, and while closely approaching the same do not bear upon or clamp the ways, sufficient looseness being allowed to avoid friction, yet permit no appreciable play. This construction of parts not only secures a true alignment of centers and reduces wear to

a minimum, but allows the stocks to move back and forth freely, as is required in a lathe of this kind, yet prevents their displacement from the ways as well as any appreciable looseness 5 or disarrangement of centers, and is hence a great improvement over the ways previously used on lathes of this kind.

The remaining feature of my invention consists in forming the gibs v' v^2 , which hold the tail-stock and tool-carriage on the ways, with projecting ribs v^3 , which admit of being filed down to take up the wear that may occur between the parts, and thus forms a simple means of neutralizing this wear, as will be readily 15 understood. It will be observed that these projections are formed on the gibs at the points where they are clamped to the base of the sliding carriage or stock, so that when the carriage has worn loose upon the ways the gibs may 20 be removed and the face of the projections filed off sufficient to prevent any play between the carriage and ways when the gibs are again fastened on.

I am aware that it is not new to provide the 25 underlying gibs of lathe-head and tail-stocks with projecting ribs, and I do not therefore claim any such construction, as the ribs heretofore employed are merely guides, and have a different function from mine, inasmuch as 30 my ribs are to prevent the ways on which my carriages move from being clamped fast between the carriage and the gib, thus allowing the carriage to move freely at all times, while the object of the gibs in the invention dis- 35 claimed is to clamp the tail-stock to the lathe and hold it fast in any desired position—a function which would be fatal to the operation of my machine if my carriages and gibs were so constructed as to be capable of performing it.

40 What I claim as my invention is as follows:

1. The combination, in a lathe with a sliding tool-holding carriage, of substantially the character shown, of a swinging shaping-tool holder and a swinging severing-tool holder, each pivoted separately and independently of the other, 45 with a wheel or equivalent device for operating said holders, and two distinct and independent connections, each extending from said wheel to a holder and operating the same, whereby each of said holders is alternately 50 brought into and out of operation, substantially as described.

55 2. The combination, with the gear-wheel w , having the wrist-pin c^2 , carrying the links z t' , of the pivoted tool-holders a b and segment y , substantially as described, and for the purpose set forth.

60 3. The combination, in a lathe with a tool-holding carriage provided with shaping and severing tools, actuated by the depression of a knee-lever or similar device, of a crank act-

uated by the same and connected with said tools, together with a coiled spring acting on the said crank, and serving by its reaction to return the crank and both tools to their positions 65 of repose, substantially as herein shown and described.

4. The combination, in a lathe with tool-holders, a device for operating the said holders, and a spring to retire the same, of a ratcheted 70 head or stop engaging one end of said spring, and permitting the adjustment of said end from one notch of the ratchet to the other, substantially as and for the purpose set forth.

5. The combination, in a lathe with tool-holders, of a cogged crank-wheel or cranked segment having its crank-pin connected with said tool-holders, together with a knee-lever formed with a segment of cogs on one arm thereof, meshing with said cogged crank, and serving 80 by its depression to actuate the said tool-holders, substantially as herein shown and described.

6. The combination, in a lathe with sliding tool-holding stocks or carriages and guiding- 85 ways, of the underlying holding-gibs v' or v^2 , detachably fastened to the base of the carriages and bearing loosely upon the under side of the ways, and formed with projections v^3 , bearing on the under side of the carriages, to prevent 90 the carriage from being clamped tightly to the ways, substantially as described.

7. In a lathe provided with a tool-holding carriage of substantially the kind shown, the combination, with the upright of the carriage 95 provided with a guiding-socket ring for the roughed work, of a roughing-tool projecting into said ring, and a tool-holder for the same connected to said upright, and adjustable by means of a screw longitudinally of the lathe 100 to and from the opening in said guide-socket, to give more or less cut to the tool, substantially as described.

8. In a lathe of substantially the kind shown, the tool-holder b , arranged horizontally, pivoted at one end, and adjustable longitudinally 105 on its pivot-stud and slotted on its free end, and provided with a tool adjustable therein, substantially as shown and described.

9. The combination, in a lathe-carriage of 110 the kind shown, of the tool-holder b , adjustable longitudinally on its pivot-stud, as set forth, with the pivot-stud t , pointed at one end and countersunk at the other, and supported at one end in a countersunk hole and at the other on 115 a pivot-screw, substantially as herein shown and described.

CHARLES W. WILDER.
